(57) **CLAIM**

The ornamental design for an engine hood for a tractor, as shown and described.

DESCRIPTION

FIG. 1 is a right front perspective view of an engine hood for a tractor;

FIG. 2 is a an enlarged right side view thereof;

FIG. 3 is a an enlarged left side view thereof;

FIG. 4 is a an enlarged front view thereof; and,

FIG. 5 is an enlarged left front perspective view thereof showing an engine hood for a tractor.

FIGS. 1, 4 and 5 show the engine hood for a tractor in its intended environment by the area having a stippled texture and outlined in dashed lines. This area is not part of the claimed subject matter. The area of the front view as shown in FIGS. 1, 4 and 5 that is hidden by portions having a stippled texture and outlined in dashed lines is not subject matter intended to be claimed.

UNITED STATES PATENT AND TRADEMARK OFFICE
CERTIFICATE OF CORRECTION

PATENT NO. : Des. 574,022 S
APPLICATION NO. : 29/273621
DATED : July 29, 2008
INVENTOR(S) : Higashikawa

Page 1 of 1

It is certified that error appears in the above-identified patent and that said Letters Patent is hereby corrected as shown below:

Face of the Patent, See the DESCRIPTION:

“FIG. 2 is a an enlarged right side view thereof;
FIG. 3 is a an enlarged left side view thereof;
FIG. 4 is a an enlarged front view thereof; and,”

should read

-- FIG. 2 is an enlarged right side view thereof;
FIG. 3 is an enlarged left side view thereof;
FIG. 4 is an enlarged front view thereof; and, --

Signed and Sealed this

Ninth Day of December, 2008

JON W. DUDAS
Director of the United States Patent and Trademark Office
